CANISTER

Charles W. Punton, Penn Township, Allegheny County, and William P. Yant, Pittsburgh, Pa., assignors to Mine Safety Appliances Company, Pittsburgh, Pa.

Application June 29, 1940, Serial No. 343,236

7 Claims. (Cl. 183—44)

This invention relates to an improvement in the construction or assembly of an air purifying canister and more particularly to a method of manufacture and the construction of a canister which can be made of relatively thin sheet metal material, which is rigid and possesses sufficient strength for all purposes for which the canister may be used, and which possesses advantages not provided in prior canister manufactures.

In breathing apparatus of the personal protection type, a canister is included in the apparatus and contains materials which remove contaminants and toxic substances from air and makes it suitable for respiration. Generally, the canister contains a mechanical filter which is made of some fibrous material and is adaptable for removing smokes, dusts and fumes, and, in addition, it contains appropriate materials for removing substances by absorption or chemical reaction. Because the canister is borne by the wearer and because of certain conditions existing in the use of the type of apparatus considered, it is necessary that any construction of the canister used must be as compact as possible and yet provide adequate space for the purifying materials. Furthermore, because of the small service time of the purifying materials contained in a canister and inability to arrange for facilities for replenishing the materials, it is necessary that the canister construction be comparatively inexpensive and be adequately strong and rigid while providing sufficient space for accommodating the materials.

It is among the objects of this invention to provide a canister construction and a method of manufacture in which the canister is adaptable to ready fabrication and is sufficiently sturdy, inexpensive and simple in construction and can be made of relatively thin sheet metal material and which can be made to accommodate materials necessary for providing a canister having adequate service time for practical purposes.

Further objects of this invention will become apparent from a description of one embodiment of my invention of a novel canister construction and that part of the invention relating to the method of manufacturing.

In the drawings:

Fig. 1 is a sectional plan view of the embodiment taken along the line 1—1 of Fig. 2;

Fig. 2 is a sectional view taken along the line 2—2 of Fig. 1;

Fig. 3 is a plan view of the same embodiment;

Fig. 4 is a detail view partly in section illustrating an assembly of a connection which forms a part of the embodiment; and

Fig. 5 is an enlarged fragmentary sectional view taken along line 2—2 of Fig. 1.

The type of canister selected for describing this invention has been used heretofore and contains an air passage through a housing and in which

is disposed the materials selected for purifying air when traveling through the passage. For the purpose of efficiency in operation, the air enters an opening in the bottom of the canister and is then deflected laterally and is constrained to pass through a mechanical filter extending along the length of the housing but inside thereof, and after passing through the filter, the air passes through chemical materials which react with or sorb the contaminants or toxic substances and complete the treatment of the air and render it suitable for respiration. A central tube collects the treated air and to which an outlet connection is attached. This connection is connected to the face-piece by means of a breathing tube and the whole canister is supported from the housing. In view of the operation of the canister, the central tube in collecting the treated air serves somewhat as a reservoir and its volumetric capacity is of much importance.

It is a feature of this invention to provide a canister of this type and containing a central tube and from which the essential operative filtering elements can be supported and which enables these parts and the connection to a demand piece of the canister to continue to be operative in an instance where an outer covering or housing usually affording the means of support is inadvertently removed or becomes so damaged that its removal is necessary. This advantage in construction is very important because of conditions met and length of use demanded of the apparatus due to lack of facilities for repair or replacement.

Referring to the drawings, the canister 1 contains a central tube 2 represented as being oblong in shape transversely of the tube, that is, having one major dimension much greater than the other and which has sufficient volumetric capacity for storing the necessary amounts of air during the cycles in the operation of the apparatus. This shape of the tube is preferred for support purposes but the invention is not limited thereto. The tube is usually disposed centrally of the surrounding functioning parts making up the canister. It is to be recognized that while in this description the tube is referred to as a central tube, this connotation is not to be considered a limitation because the tube can be disposed in any other manner relative to the other parts without departing from the scope of this invention. The tube is made of thin sheet metal as well as are other elements making up the canister assembly and the tube is of a perforated wall section for the most part to receive the air after being treated, and for some purposes, it is necessary to further restrict the perforations by applying a thin fabric material on the outside of the tube since it has been found in manufacture to be advantageous to use perforated material of a size having openings larger than necessary and then

constrict the openings by use of fabric material. The fabric is represented as 3 and completely encloses the perforated section and is attached to the body of the tube by means of an adhesive tape 4.

The upper end portion of the tube 2 represented as 2a is illustrated in the drawings, Figs. 2 and 5, as being made of a piece separate from the perforated section and joined by any suitable means, but, as is obvious, this end portion and the perforated portion can be made of one piece of material so that the central tube, hereinafter identified as 2, is composed of the whole duct extending from the upper portion 2a to and including the lower portion 2b. The upper end 2a has attached an intermediate metal connector or upper lateral extension 5 having a flange 5a abutting the surface of the tube and which can be fastened by means of soldering or any of the other expedients for attaching thin metal surfaces, or it can be made integral therewith and provided in shaping the tube. The outer extent of this extension contains a depending flange 5b which abuts a similar surface of an outlet connection 6. The outlet connection 6 to be connected to a breathing apparatus (not shown) contains at its receiving end an outer depending flange 6a to which an inner perforated wall or housing member 7 is connected.

The lower extent of the breathing tube 2b has a cup 8 resiliently engaging the lower portion of the tube proper and closing off its opening at this extent. Supported thereto is a lower lateral extension 9 having portions 9a upstruck from a flat surface and in a manner to accommodate the cup 8 so as to position the cup and the tube in proper relation to the member 9. This arrangement allows some tolerance in manufacture but modifications can be made readily as by extending the upstruck portions 9a to serve the same purpose as the cup 8. This member 9 has an outer flange 9b to which the inner wall 7 is attached at its lower extremity. This wall 7 defines an inner chamber 20 for accommodating and confining the chemical materials 29a that are disposed in the path of air to be treated. A mechanical filter means 10 which may be a fibrous material suitably impregnated to remove dusts and smokes and solid particles suspended in the air is wrapped around the outer surface of the wall in some fashion as in a spiral manner and is held thereto by means of resilient clips 11 and 12 at each end of the filter. An outer housing or carriage member 13 containing corrugations or outwardly extending bulges 13a provided in order to grip a fabric harness is connected to the central tube and in spaced relation to the outermost surface of the filter 10 by means of a metal connector 14 which engages a surface of the outlet connection 6 and to which the central tube is connected through the lateral extension 5. It has been found that by crimping the edges of both the outer housing 13 and the connector 14 that a suitable connection is provided and it allows quick removal of the outer housing from the filtering parts of an operative air purifying canister, should it become necessary. The lower end of the housing is connected to a base member 15 which extends outwardly a sufficient distance to dispose the lower extent of the housing in alignment with the upper extent and it is attached thereto by crimping as used in connecting the upper end of the tube. This base member contains an inlet opening 16 which is controlled

by a valve 17 composed of a thin rubber plate or disc which covers the opening 16 represented as a series of small openings 16a, Fig. 1. In order to space the base member 15 from the under surface of the lower lateral extension 9 and to support the functioning parts of the canister from the housing or carriage member 13, separate upstanding extents 18 integral with the base member engage the surface of the member 9 and space the base member therefrom. These extents are so made that an outside surface 18a engages the flange surface 9b inwardly of the section illustrated in Fig. 2 so as to hold the member 9 in place relative to housing member 13, and they are much smaller at the upper extremity than at the base in order to provide an adequate passage from the inlet opening 16 to the space provided between the inner and outer housing members 7 and 13. As is obvious, this space between the housing members should be sufficient to accommodate the mechanical filter 10 and also provide a space between the outer surface of the filter and the surface of the housing 13 to allow free passage of air over the entire operative surface of the filter and limit the resistance to movement of air as much as possible.

In the operation of this canister, air is drawn through the inlet opening 16 during inhalation of the wearer and by the force of suction the air passes between the base member 15 and the lower lateral extension 9 to the space between the filter 10 and the outer housing 13. The air then passes through the mechanical filter and the chemical materials designated as 29 and then into the space provided by the central tube 2. From here the air then passes through the outlet connection 6 and into a breathing tube (not shown) and to which is connected a face-piece worn by the user.

In the attachment of the various flat surfaces or flanges of the several component members to a comparable surface of an abutting member, any means of permanent attachment can be used, and it has been found that soldering itself provides a sufficiently strong connection for engaging the separated parts which are to be attached, except that the attachment of the outer housing 13 to the central tube is by crimping to allow ready removal of the housing if necessary. The attachment of the housing 13 to the base member 15 is by crimping and it is apparent that these two members could be made of a single piece although for manufacturing it is preferred that they be made as represented. It is apparent from this description that the functioning of the canister as an operative unit does not require the outer housing 13 as a means of support and all the necessary parts are supported either directly or indirectly from the central tube 2. By this arrangement, in the event that it becomes necessary to remove the carriage or outer housing member 13, the canister can be carried by means of the outlet connection which in turn is attached to the central tube and from which the parts supporting the purifying materials are supported. The resilient attachment of the central tube to the lower lateral extension 9 by means of cup 8 allows for variations in the length of the tube and in the assembly, since it has been found that it is more practical to provide this member than extend the upstruck portions 9a a sufficient distance to accommodate the variations that may occur.

Another feature of this invention is that the

fabrication of the canister is adaptable to a novel method of construction of a canister and a description of a preferred method will disclose the principle involved thereof. In this method of manufacture, the central tube 2 is made from a flat perforated sheet by suitable shaping and crimping. A fabric is then applied to the outer surface to restrict the openings to the desired extent and is fastened by means of a suitable adhesive or tape. To this tube, the intermediate member 5 is attached and to which the outlet connection has previously been attached. The inner wall member 7 is then connected to the flange surface of the outlet connection 6, and at this stage of assembly the chemical material is then placed in the intermediate chamber 20 thus formed. The cup 8 and lower lateral extension 9 are then added to the central tube and the latter is attached to the lower end of the inner wall 7. The mechanical filter 10 is then attached to the outer surface of the inner wall 7 by resilient clips 11 and 12. The housing 13 and base member 15 are connected together by crimping preliminary to their assembly to the filter unit and then the unit is passed thereinto and positioned onto the extents 18. The connector 14 is connected to the housing 13 and soldered to the outlet connection 6. It has been found that if housing 13 is made a trifle shorter than required that the assembly will distort the connector 14 and make it operative as a spring member. This result is beneficial because it acts as a means to place a slight strain on the engagement of the connector 14 with the outlet connection 6 and provides a tight attachment of the lower member 9 to the extents 18 and prevents any lateral movement of any of the parts within the housing 13 which might prove destructive and which may occur by rough handling. It is apparent that this series of steps in manufacture describe one embodiment of the general sequence which is to be followed, but it is recognized that other methods can be devised which will incorporate the general sequence developed.

From this description of our invention, it is to be observed, also, that the elements making up the canister can be readily fabricated and by reason of their construction and arrangement provide ample rigidity and sturdiness to a complete canister while providing the necessary space for accommodating the passages and air purifying materials contained within the canister and lend themselves readily to our method of manufacture. Furthermore, by the arrangement the joints formed by the engagement of the separated parts adapt themselves readily to any available practical process used for connecting such parts. Other advantages are present which are obvious from the above description of the preferred embodiment of our invention.

It is intended that this detailed description of the construction of the canister be for the purpose of a full and complete description of the adaptation of our invention to one embodiment incorporating the principle and mode of operation of our invention and within the scope of the appended claims, and we desire to have it understood that the invention may be practiced otherwise than as specifically illustrated and described.

We claim:

1. A rigid fabricated sheet metal canister comprising a central perforated tube and support member having a transverse oblong shape, an upper lateral extension support member having

an abutting surface engaging a surface of the tube and being connected thereto, an outlet connection member having a surface engaging a surface of the lateral extension support member and being attached thereto and having a passage connected to the passage of the central tube, a lower lateral extension member having a portion upstruck to define an upstanding receptacle to receive and close off the lower end of the central tube and to resiliently engage and be supported therefrom, an inner perforated housing member engaging a surface of the outlet connection and the lower lateral extension and being fastened thereto and defining an air purifying material compartment, an outer and detachable housing member supported from the outlet connection and defining an enclosed space between the housing members in which a filter can be positioned against the surface of the perforated member, and a bottom piece attached to the outer housing and containing an inlet opening and having a means to engage the lower lateral extension and provide a passage therebetween and connecting the inlet opening to the passage between the housing members.

2. A fabricated sheet metal canister comprising a perforated tube and support member having a transverse oblong shape, an upper lateral extension support member having an abutting surface engaging a surface of the tube and supported therefrom, an outlet connection having a surface engaging and attached to a surface of the lateral extension support member and having an inner transverse dimension comparable to the width of the tube, the tube and outlet connection being disposed so that the tube-engaging portion of said lateral extension member engages the wall of the outlet connection and the passage of the outlet connection is in alignment with the passage of the tube, a lower lateral extension having a portion upstruck to provide an upstanding receiving portion, an intermediate receptacle resiliently engaging the portion and receiving and closing off the lower end of the tube and supported therefrom, an inner perforated housing member engaging a surface of the outlet connection and the lower lateral extension and fastened thereto and defining an air purifying material compartment, an outer carriage member having spaced corrugations and detachably supported from the outlet connection in spaced relation to the housing member to define a passage therebetween and in which a filter means can be positioned against the surface of the inner housing and provide an air passage across the surface of the filter means, said carriage member including a bottom portion containing an inlet opening and carrying upstanding spaced members to engage the lower lateral extension member to space the bottom portion from the lower lateral extension and provide a passage connecting the inlet opening to the perforated housing member.

3. A fabricated sheet metal canister comprising a perforated tube and support member having a transverse oblong shape, an upper lateral extension support member having an abutting surface engaging a surface of the tube and supported therefrom, an outlet connection having an undersurface engaging and attached to an outer surface of the lateral extension support member, the inner wall surface of the connection defining a width of passage substantially that of the width of the tube, the tube and outlet connection being disposed so that the tube-engaging portion of said lateral extension member engages the inner

wall of the outlet connection and the passage of the outlet connection is in alignment with the passage of the tube, a lower lateral extension having a portion upstruck to provide an upstanding receiving portion, an intermediate receptacle resiliently engaging the portion and receiving and closing off the lower end of the tube and supported therefrom, an inner perforated housing member engaging a surface of the outlet connection and the lower lateral extension and fastened thereto and defining an air purifying material compartment, suitable materials in the compartment, a mechanical filter means attached to the surface of the inner housing, an outer carriage member having spaced corrugations in its side wall and attached to an outer surface of the outlet connection in spaced relation to the outermost surface of the filter means and provide an air passage across the surface of the filter means, said carriage member including a bottom portion containing an inlet opening carrying upstanding spaced members to engage the lower lateral extension member to space the bottom portion from the lower lateral extension and provide a passage connecting the inlet opening to the passage above the filter means.

4. A fabricated sheet metal canister comprising a perforated tube and support member having a transverse oblong shape, an upper lateral extension support member having an abutting surface engaging a surface of the tube and supported therefrom, an outlet housing connection having an undersurface engaging and attached to an outer surface of the lateral extension support member, the transverse dimension of the inner wall of the outlet connection being of substantially the same size as the greater dimension of the tube, the tube-engaging portion of said lateral extension member engaging the inner wall surface of the outlet connection and the passage of the outlet connection being in alignment with the passage of the tube, a lower lateral extension having a portion upstruck to provide an upstanding receiving portion, an intermediate receptacle resiliently engaging the portion and receiving and closing off the lower end of the tube and supported therefrom, an inner perforated housing member engaging a surface of the outlet connection and the lower lateral extension and fastened thereto and defining an air purifying material compartment, suitable materials in the compartment, a mechanical filter means attached to the surface of the inner housing, an outer carriage member having spaced corrugations in its side wall and having a surface attached to an outer surface of the outlet connection in spaced relation to the outermost surface of the filter means, said carriage member including a bottom portion containing an inlet opening and carrying upstanding spaced members to engage the lower lateral extension member to prevent any lateral movement thereof and to space the bottom portion from the lower lateral extension and provide a passage connecting the inlet opening to the passage above the filter means, and the attachment of the carriage member being such as to produce strain on the engaging parts of the canister and provide a rigid assembly.

5. A fabricated sheet metal canister comprising a tubular outlet connection member having at its lower end a laterally extending flange, said flange having a downturned portion spaced inwardly from its outer edge to form a continuous

shoulder, a lateral extension member in the lower end of the outlet connection provided centrally with a restricted opening and having its marginal portion connected to the inside of said shoulder, a central perforated tube having its upper end attached to the lateral extension member in said opening, means closing the lower end of said tube, a bottom plate below the tube, an inner perforated wall member attached to the outer edge of said flange and to said bottom plate for defining an air-purifying material compartment around the central tube, a filter positioned against the outer surface of said inner perforated wall member, a protective housing surrounding the filter and spaced therefrom and provided with an air inlet, and a ring connecting the upper end of the housing to the outside of said shoulder to support the housing therefrom.

6. A fabricated sheet metal canister comprising a tubular outlet connection member having at its lower end a laterally extending flange, said flange having a downturned portion spaced inwardly from its outer edge to form a continuous shoulder, a lateral extension member in the lower end of the outlet connection provided centrally with a restricted opening and having its marginal portion connected to the inside of said shoulder, a central perforated tube having its upper end attached to the lateral extension member in said opening, a bottom plate below the tube, a cup mounted on the plate and resiliently gripping the lower end of said tube to close it, an inner perforated wall member attached to the outer edge of said flange and to said bottom plate for defining an air-purifying material compartment around the central tube, a filter positioned against the outer surface of said inner perforated wall member, a protective housing surrounding the filter and spaced therefrom and provided with an air inlet, and a ring connecting the upper end of the housing to the outside of said shoulder to support the housing therefrom.

7. A fabricated sheet metal canister comprising a tubular outlet connection member having at its lower end a laterally extending flange, said flange having a downturned marginal portion and having a down-turned portion spaced inwardly therefrom to form a continuous shoulder, a lateral extension member in the lower end of the outlet connection provided centrally with a restricted oblong opening and having a down-turned marginal portion connected to the inside of said shoulder, a central perforated tube oblong in transverse section attached at its upper end to the lateral extension member in said opening, means closing the lower end of said tube, a bottom plate below the tube, an inner perforated wall member attached to said down-turned marginal portion of said flange and to the edge of said bottom plate for defining an air-purifying material compartment around the central tube, a filter positioned against the outer surface of said inner perforated wall member, a protective housing surrounding the filter and spaced therefrom and provided with an air inlet, and a ring connected to the upper end of the housing and extending inwardly therefrom, the inner marginal portion of the ring being down-turned and attached to the outside of said shoulder to support the housing therefrom.

CHARLES W. PUNTON.
WILLIAM P. YANT.
